US00D969059S

(12) **United States Design Patent** (10) Patent No.: **US D969,059 S**
Huang (45) Date of Patent: **** Nov. 8, 2022**

- (54) **BIKE RACK HOOK PROTECTOR**
- (71) Applicant: **Shuo Huang**, Xingning (CN)
- (72) Inventor: **Shuo Huang**, Xingning (CN)
- (73) Assignee: **Shenzhen Mierbaby Technology Development Co., Ltd.**, Shenzhen (CN)
- (**) Term: **15 Years**
- (21) Appl. No.: **29/804,663**
- (22) Filed: **Aug. 22, 2021**
- (51) LOC (13) Cl. **12-11**
- (52) U.S. Cl. **USPC D12/407**
- (58) Field of Classification Search **USPC D12/406-408, 115; D8/367, 372, 373; D22/144; D6/328, 552 CPC .. B60R 9/10; B60R 9/06; B60R 11/00; B62H 3/00; B62H 3/12; A47F 5/0876; F16B 45/00**
